DESIGN FOR A CASKET TABLE CORNER PLATE FOR HEARSE

Earl L. Schofield, Freeport, Ill., assignor to Hen-
ney Motor Company, Freeport, Ill., a corpora-
tion of Delaware

Application October 26, 1936, Serial No. 65,520

Term of patent 14 years

To all whom it may concern:

Be it known that I, Earl L. Schofield, a citizen of the United States, residing at Freeport, in the county of Stephenson and State of Illinois, have invented a new, original, and ornamental Design for a Casket Table Corner Plate for Hearses, of which the following is a specification, reference being had to the accompanying drawings forming part thereof:

In the drawings:

Figure 1 is a perspective view of a casket table corner plate for hearses embodying the design of my invention;

Fig. 2 is a side view of Fig. 1;

Fig. 3 is a plan view of the corner plate;

Fig. 4 is an end view of Fig. 3;

Fig. 5 is a section on the line 5—5 of Fig. 3, and

Fig. 6 shows the left-hand end portion of Fig. 4.

In the various views the stippling indicates contrasting color.

I claim:

The ornamental design for a casket table corner plate for hearses, substantially as shown and described.

EARL L. SCHOFIELD.
